UNITED STATES PATENT OFFICE.

FORD W. HARRIS, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-CONTROLLER.

1,162,056.

Specification of Letters Patent. Patented Nov. 30, 1915.

Application filed December 5, 1910. Serial No. 595,637.

To all whom it may concern:

Be it known that I, FORD W. HARRIS, a citizen of the United States, and a resident of Wilkinsburg, in the county of Allegheny and State of Pennsylvania, have invented a new and useful Improvement in Circuit Controllers, of which the following is a specification.

My invention relates to circuit controllers for electrically operated apparatus, and it has special reference to remote-control circuit interrupters of comparatively large capacities.

The object of my invention is to provide a controlling device of the class above indicated which shall be rugged and durable in construction, reliable and effective in operation and particularly adapted to introduce a sufficient time element into its action to insure the proper operation of an electrically operated circuit interrupter, or other device, with which it may be associated.

In power station practice, where enormous amounts of power are handled by comparatively few circuit interrupters, it is of utmost importance that absolutely reliable operation be secured. It is customary for circuit interrupters employed in this class of service to be provided with electrically operated closing and tripping coils which, in general, may be depended upon for reliability of operation if the time of energization is sufficient to allow the magnetism of the coils to build up to its maximum. Heretofore, frequent difficulties have been experienced on account of careless manipulation by the station operators, and it is to obviate the possibility of such troubles that my controlling device is particularly intended.

According to my invention, I provide a circuit controller of the drum type which is biased to its "off" position under all operating conditions but which may be moved in opposite directions to complete energizing circuits for the closing or tripping coils of a circuit interrupter. Furthermore, the mechanism of the controller is so constructed that, when moved into or out of either of its operating positions, the circuit is completed or interrupted with a snap movement, thereby eliminating arcing and the consequent burning of the contact fingers. Moreover, I associate a time-element device therewith, so that when either energizing circuit is once

completed, it remains so a sufficient time to insure certain operation of the circuit interrupter, after which the controller is automatically returned to its neutral position and a quick break of the coöperating contact members is effected.

My invention may best be understood by reference to the accompanying drawings, in which—

Figure 1 is a view, partially in side elevation and partially in vertical section, of a controlling device constructed in accordance with my invention. Fig. 2 is a detail end view of the locking mechanism shown in Fig. 1. Fig. 3 is a detail end view of the eccentric and dash pot shown in Fig. 1, and Figs. 4, 5 and 6 are diagrammatic views, showing the relationship of certain parts of the controlling device during successive steps in its operation.

Referring to the drawings in detail, the circuit controller comprises a supporting frame 1, an operating shaft 2, a drum 3, movable contact terminals 4, stationary contact fingers 5, an operating handle 6, a centering spring 7, an actuating mechanism 8, a locking mechanism 9, and a time-element device 10.

The operating shaft 2 is rotatably mounted in bearings 11 provided in end plates 12 of the supporting frame 1, and the drum 3 is loosely mounted upon one end of said shaft and carries a row of stationary contact terminals 4. The stationary contact fingers 5 are disposed in rows on opposite sides of the drum 3 and are so located as to coöperate with the movable contact terminals 4 when the drum 3 is moved into either of its operating positions. An end plate member 13, which is also loosely mounted upon shaft 2 and is rigidly associated with the drum 3, is provided with longitudinally projecting arms 14 and 15 for purposes to be herein-after explained.

The operating handle 6 is fixed to one end of the shaft 2 and is adapted to be moved in either direction in opposition to the centering spring 7, which biases the handle to its neutral position under all operating conditions.

A spring retaining member 16 is pinned to the shaft 2 and comprises a hub portion 16a about which the spring 7 is disposed, and a T shaped portion 17, having oppositely projecting longitudinal arms 18 and 19.

19. A projecting arm 20 forms an integral part of the front end plate 12, and ends 21 and 22 of the spring 7 are located on opposite sides of the arms 18 and 20 in such a manner that movement of the operating handle in either direction produces tension in the spring 7, as will be readily understood.

20 The actuating mechanism 8 comprises coil springs 23 and 24 and an intermediate member 25 which is loosely mounted upon the shaft 2. The intermediate member 25 is of compound structure and its component parts include a centrally located eccentric disk or sheave 26, flanged end plates 27 having projecting portions 28, and spring-holding members 29 and 30, all of said parts being secured together in a suitable manner to provide a single unit. Longitudinally disposed arms 31 and 32 are provided upon the spring-holding members 29 and 30, respectively.

21 The coil springs 23 and 24 respectively surround the spring-holding members 29 and 30 and said springs are of materially less strength than the centering spring 7, spring 24 being the weaker of the two. The ends 33 and 34 of the springs 23 and 24 are located on the respective sides of the arms 19 and 31, and the arms 14 and 32, respectively, in order that movement in either direction may produce a tension therein, as will be readily understood.

22 A cam member 35 forms an integral part of the spring-holding member 30 and projects into an opening 36 which is centrally located in a disk member 37. The disk member 37 is movably associated with the end plate member 13, and is provided with oppositely disposed projecting portions 38 and 39 which are loosely fitted into openings 40 and 41 which are provided in the arms 14 and 15, respectively. An angle member 42 is secured to one face of the disk 37 and a spring 43 is located between said angle member and the arm 14, in order to maintain the disk member 37 in its lower position, thereby causing projection 39 to engage a notch 44 provided in a stationary bracket 45. The bracket 45 is further provided with notches 46 and 47 which coöperate with the projection 39 when the controller is in either of its operating positions.

23 An eccentric strap 48 surrounds the disk or sheave 26 in the usual manner and is pivotally associated with a connecting rod 49 which is connected to a piston 50 of a dash pot 51 by means of a lever 52 and a connecting link 53.

24 The construction and mode of operation of the coöperating parts of the eccentric are old and familiar in the art and no detailed description is considered necessary. Moreover, the dash pot is also of well known construction and operates in the usual manner.

25 It will be observed, however, that the piston 50 is provided with holes 54 and a floating disk member 55 by means of which the dash pot performs its intended function only during its upward movement, as will be readily understood.

26 Assuming the controlling device to be in its neutral position and the various parts to occupy the positions shown in Figs. 1, 2 and 3, the operation is as follows: If the operating handle 6 be moved for example in clockwise direction, as viewed from the front end of the controlling device, to one of its operating positions, it is evident that tension is produced in the spring 7 which tends to return the operating handle to its neutral position. Moreover, springs 23 and 24 are placed under tension and the intermediate member 25 is rotated in a clockwise direction by reason of the difference in the strengths of the springs 23 and 24. As the intermediate member 25 is rotated, the piston 50 is forced downwardly through the agency of the eccentric but by reason of the peculiar construction of said piston, no delayed action of the intermediate member is effected. Moreover, as the intermediate member 25 is rotated, the cam member 35 cooperates with the edge of the opening 36 in the disk member 37 and, when a predetermined rotative movement is effected, a projecting portion 56 of said cam forces the disk 37 to its upper position and thereby releases the projection 39 from the notch 44, as shown diagrammatically in Fig. 4. Upon the release of the locking mechanism 9, the drum 3 is actuated in a clockwise direction by means of the springs 23 and 24 and a sudden engagement of the coöperating movable and stationary contact members 4 and 5 is effected. The springs 23 and 24 are, therefore, relaxed and exert no force upon the drum 3. As the drum 3 and its associated disk member 37 are actuated, the projecting portion 56 of the cam member 35 is disengaged from the edge of the opening 36, and the spring 43 causes the projection 39 to engage the notch 46 in the stationary bracket 45, when the controller is in its operating position. The relationship of the various parts is shown diagrammatically in Fig. 5. If the operating handle 6 be now released, the spring 7 returns it to its neutral position and thereby produces tension in the spring 23, as will be readily understood. By reason of the excess strength of the spring 23, the intermediate member 25 is gradually rotated in a counter-clockwise direction against the action of the dash pot 51, which, in its upward movement, introduces a time-element into the operation. As the intermediate member 25 is gradually rotated by the spring 23, potential energy is stored in the spring 24 until the projecting portion 57 of the cam member 35 causes the

release of the projection 39 from the notch 46, as shown in Fig. 6. As soon as the locking device 9 is released, the drum 3 is actuated in a counter-clockwise direction by means of springs 23 and 24 and a quick disengagement of the coöperating contact terminals 4 and 5 is effected, the various parts of the controlling device assuming their initial neutral positions.

Those skilled in the art will readily understand that, by proper adjustments of the dash pot 51, a minimum allowable time of engagement of the coöperating movable and stationary contact members 4 and 5 may be obtained. Hence it is possible to adjust the controlling device to maintain contact a sufficient length of time to allow the magnetism in the coils of an electrically operated circuit interrupter (not shown) to build up to its maximum value and thus insure positive and reliable operation.

The operation of the controlling device in the opposite direction is similar to that hereinbefore described and, on account of its similarity, no further description is considered necessary.

Although I have shown and described a controlling device of specific structure and mode of operation, it is evident that many modifications in the arrangement and location of parts may be effected without departing from the spirit and scope of my invention, and I desire that only such limitations shall be imposed as are indicated in the appended claims.

I claim as my invention:

1. A controller comprising a plurality of stationary and movable coöperating contact members, said movable contact members being adapted to be moved in opposite directions, means for automatically returning said movable contact members to their "off" position and means for delaying such action.

2. A controller comprising stationary contact terminals, a coöperating contact-bearing member adapted for movement in either direction from a neutral position, means for biasing said contact-bearing member toward its neutral position, and a time-element device associated with said contact-bearing member.

3. A controller comprising stationary and movable contact members, means for biasing said movable contact members toward their "off" position, adjustable means for delaying the action of said movable contact members, and means for effecting engagement and disengagement of said coöperating contact members with a snap movement.

4. A controller comprising stationary contact members, coöperating movable contact members adapted to be moved in opposite directions, a single means for biasing said movable contact members to their "off" position, adjustable means for delaying the ac-

tion of said movable contact members, and means for causing a sudden movement of said movable contact members.

5. A drum controller comprising stationary contact members, coöperating movable contact members, an operating handle for said movable contact members, means for automatically returning said handle to its "off" position, means for moving said movable contact members subsequent to the movement of said operating handle, and means for delaying the movement of said movable contact members a predetermined amount.

6. A drum controller comprising stationary contact members, coöperating movable contact members, an operating handle resiliently associated with said movable contact members and adapted to be moved in opposite directions, a single means for automatically returning said handle to its "off" position, means for actuating said movable contact members subsequent to the movement of said operating handle, and means for delaying the movement of said movable contact members a predetermined amount.

7. A controller comprising stationary and movable coöperating contact members, an operating handle adapted to be manually operated in opposite directions, means for returning said handle to its "off" position, resilient means for causing sudden movement of said movable contact members subsequent to the movement of said operating handle, and means for delaying the sudden movement of said movable contact members.

8. A controller comprising a drum having a plurality of contact members, a plurality of stationary contact members to coöperate therewith, an operating shaft loosely fitted through said drum and resiliently connected thereto, an operating handle fixed to said shaft, means for preventing the movement of said drum until said handle is moved a predetermined amount, means for effecting a snap movement of said drum, means for returning said operating handle to its "off" position, and means for delaying the action of said drum subsequent to the movement of said operating handle.

9. A controller comprising coöperating stationary and movable contact members, an operating handle associated with said movable contact members and adapted to be manually moved in either direction, a single means for automatically returning said handle to its "off" position, and means for actuating said movable contact members a predetermined time after the movement of said handle.

10. A controller comprising a supporting frame, an operating shaft rotatably mounted therein, a drum loosely mounted on said shaft, contact members secured to said drum, stationary contact members to coöperate

therewith, a spring to return said shaft to its "off" position, an intermediate member loosely mounted on said shaft, a spring disposed between said shaft and said intermediate member, a second spring disposed between said intermediate member and said drum, a mechanical locking device associated with said drum, a cam associated with said intermediate member and adapted to 10 release said locking device under predeter-

mined conditions, an eccentric associated with said intermediate member, and a dash pot connected to said eccentric.

In testimony whereof, I have hereunto subscribed my name this 29th day of November, 1910.

FORD W. HARRIS.
